UNITED STATES PATENT OFFICE.

HERMANN T. WERBER, OF BROOKLYN, NEW YORK.

TURBINE.

Application filed October 27, 1923. Serial No. 671,190.

This invention relates to turbines and more particularly to improvements in the blade constructions thereof.

In the usual construction of devices of this character it is the common practice to construct the stator and rotor elements of a plurality of blades which are intended to be detachably mounted upon ring structures so as to enable a damaged blade to be replaced when necessary. In order to accomplish this intended detachability of the blades, the rings are provided with a T-shaped groove having an entrance slot through which a T-shaped end of each blade is inserted, the blades being inserted within the groove and pushed around the ring until all of the blades are placed upon the rings. In order to hold the blades in properly spaced relationship, wedges are driven in between adjacent blades. While this structure theoretically provides means for detaching the blades, in actual practice it is found impossible to move the blades around the rings after the turbine has been operated for a comparatively short time, and it becomes necessary either to cut or burn the whole set of blades away when replacement becomes necessary. The blades of the stator and rotor elements are also arranged to produce a series of deflections or reversals of the direction of the flow or passage of the steam or other fluid passing through the device, which deflections are produced along longitudinally extending lines. I have discovered that by providing additional guiding surfaces on the blades to produce a series of radially extending reversals or deflections in addition to the longitudinal deflections, that I am able to greatly increase the efficiency of the turbine due to the fact that such guiding surfaces not only furnish additional surface area against which the force of the fluid is exerted without increasing to an appreciable extent the weight of the moving parts, but also because the said guiding surfaces are employed to define a series of alternately arranged nozzles and expansion chambers. It therefore is the principal object of this invention to provide a new and improved construction of the turbine blades by means of which an additional series of deflections or reversals of the steam or other fluid will be produced along radially extending lines in addition to the heretofore mentioned longitudinal deflections or reversals.

A further object is to provide a new and

improved construction for detachably securing the removable blades so as to overcome the difficulties of removing the blades as heretofore constructed and by means of which new construction one or more blades may be replaced at any desired point about the circumference of the ring surfaces without disturbing any of the blades other than those to be replaced.

Another object is to provide the outer ends of the blades with an enlarged or thicker portion which prevents the passage of the steam in a radial direction past the outer ends of the blades and to also shape these outer thicker portions so that adjacent blades, when placed in position, will contact with each other along plane surfaces in nested relationship and thereby effectually prevent lateral displacement of the blades and consequent damage thereof during the operation of the turbine. For the accomplishment of these and such further objects as will be apparent to those skilled in the art to which this appertains, the invention consists in the construction, combination and arrangement of parts, an embodiment of which is hereinafter more specifically described and is illustrated in the accompanying drawings forming a part hereof, but it will be understood that changes, variations and modifications may be resorted to without departing from the spirit of my invention.

Referring to the drawings, Figure 1 is a side view partly in section and partly in elevation of an assembled turbine; Fig. 1^a is an enlarged detail of one of the turbine blades; Fig. 2 is a section on the line 2—2 of Fig. 1; Fig. 3 is a detail in perspective of the blade structure; Fig. 4 is a section substantially on the line 4—4 of Fig. 1 showing in a somewhat exaggerated form the gradual enlargement of the steam passages formed between the blades from the entrance to the delivery end of the turbine; Fig. 5 is a sectional detail of a blade and a portion of the ring structure therefor showing the manner in which the blades are secured to or removed from the ring structure and Fig. 6 is an elevation of the nozzle plate at the entrance end of the turbine.

As shown in the drawing the numeral 10 indicates the outer cylinder or casing of the turbine which, it will be noted, diverges from the left, the entrance end, to the right, the delivery end. The front cylinder head

11 of the turbine at entrance end is preferably integral with the cylinder 10 and the delivery end is closed by a cylinder head 12, which is detachably mounted to the cylinder by means of the bolts 13. Steam admission and delivery ports 14 and 15 are provided in the cylinder heads 11 and 12 respectively in accordance with the usual practice.

16 The steam entering through admission port 14 passes into a distribution chamber 16 in which a nozzle plate 17 is mounted, said nozzle plate being provided with a plurality of nozzle passages 18 which are inclined towards the longitudinal axis of the turbine and also in the direction of rotation thereof as will be clearly seen from an inspection of Figs. 1 and 6. The nozzle plate 17 is non-rotatably secured to the cylinder 10 or the cylinder head 11 in any suitable manner.

17 Rotatably mounted in bushings 19 and 20 secured in the bosses 21 and 22 of the cylinder heads 11 and 12, respectively, is the driving shaft 23 which has secured thereto, a plurality of ring structures 24 which form with the blades 25 the rotor elements of the turbine.

18 The stator elements of the turbine are formed by the blades 26 which are secured within T slots 27 either formed directly in the cylinder or in rings suitably secured thereto, while the rotor elements are attached to the rings 24 in similar T slots 28 provided in said rings.

19 Each of the blades 25 and 26 consists of an attachment portion 29 and a steam passage portion 30, and the construction of both stator and rotor blades are similar with the exception that the attachment portions of the rotor blades taper outwardly towards the steam passage portion thereof while on the stator blades the taper is opposite (see Fig. 2).

20 The steam passage portion 30 of the blades 25 and 26 (see Figs. 1, 3 and 4) consists of a pair of walls 31 and 32 substantially at right angles to one another and which terminate at their ends in the thickened end portions 33 and 34, which define the ends of the steam passages formed between the blades.

21 That part of the thickened end portions which extends across the wall 31 forms the guiding surfaces 35 and 36 which are substantially parallel with each other and with the longitudinal axis of the turbine (considered radially) while the guiding surfaces 37 and 38 formed by the thickened end portions across the wall 32 extend at an angle to the guiding surfaces 35 and 36. The space between the guiding surfaces 35 and 36 and the walls 31 of adjacent blades when they are in juxtaposition, forms, in effect, a small expansion chamber 39 through which

22 the steam passes in a substantially longitudinal direction and from which it flows to the space between the guiding surfaces 37 and 38 and the walls 32 of the adjacent blades. This latter space is preferably subdivided by the partitions 40 to form in effect a plurality of nozzles 50, extending at an inclination to the radii. By referring to Fig. 1 it will be noted that the nozzles formed by the blades 25 of the rotor elements, direct the steam away from the axis while those formed by the stator blades direct the steam towards the axis.

23 The steam passages formed by the blades 25 and 26 expand gradually, considered both 24 radially and longitudinally, from the entrance to the delivery end of the turbine, as will be noted by referring to Figs. 1 and 4 of the drawings, Fig. 1 showing the expansion considered radially, and Fig. 4 the longitudinal expansion.

25 The attachment portion of each blade 25 and 26 is slotted out as at 41 (Figs. 1 and 3) to provide a T head which is adapted to be engaged within the T slots 27 and 28 and 90 in order that a blade may be inserted at any point along the circumference of the slots, the thickness of the attachment portion is made slightly less than the open end of the slots as shown in dotted lines Fig. 5, while the side edges of the T heads are slightly rounded or backed off as at 42 to permit the blades to be readily turned from the dotted to the full line position shown in said figure. In attaching the blades therefore, it is only necessary to insert the T heads of the blades at the places they are to occupy into the open ends of the T slots, as indicated in the dotted lines, and then to turn the blades through an angle of 90° to the full line positions, thereby obviating the necessity of pushing the blades around the T slots from a single entrance hole as in the usual constructions. The last blade to be inserted is not provided with a T head but the laterally projecting lugs which form the T head are removed in any suitable manner, for example, by chipping or filing, and the blade is then inserted and firmly wedged in place by driving it into its slot 110 in a direction radially of the turbine shaft, after which it is welded to the adjacent blades. After the blades are placed in position they are so proportioned and arranged that they will lie in nested contacting positions as shown in Fig. 3, and the outer meeting edges of the blades are slightly welded, brazed or soldered, to form each stator and rotor element into a substantially integral, 115 unitary structure.

120 The operation of the turbine is as follows:

125 Steam enters the turbine through admission port 14 and passes from the distribution chamber 16 to the nozzles 18 by which

it is directed in an inclined direction towards the axis and also at an angle towards the delivery end into the chambers 39 of the first rotor element. The steam impinging 5 against the inclined walls 31 of the blades 25 of the first rotor element will impart a rotary movement thereto. From the chambers 39 the longitudinal direction of the steam is reversed by the walls 32 and also 10 a radial deflection is imparted by the nozzles 50 formed by the guiding surfaces 37 and 38, and the walls of the partitions 40, which partitions are parallel to the guiding surfaces 37 and 38. The outward radial deflection of the steam as it passes the rotor 15 elements is also assisted by rotation of the rotors tending to exert a centrifugal effect upon the steam. As the steam leaves the nozzles 50 formed by the blades of the rotor 20 elements, it passes into the expansion chambers 39 of the stator elements and is then deflected both longitudinally and radially towards the axis by the nozzles 50 of the stator blades. By the provision of the thickened 25 end portions 33 and 34 a series of closed chambers are provided against the inclined walls of which the force of expansion of the steam is exerted in practically all directions thereby utilizing substantially the full power 30 thereof, the reaction of the steam against the inclined surfaces 35 and 36 as well as the partitions 40 having a component which will exert a driving torque to the rotor elements, which will supplement the torque produced 35 against the radially extending surfaces of the walls 31 and 32 by the longitudinal reversals of the steam. The inclined surfaces also are employed, in conjunction with the partitions 40, to form a plurality of nozzles 40 which serve to produce a succession of jet effects on the fluid after it passes through each expansion chamber and as it is passing from each respective blade, whether stator or rotor to the next succeeding blade.

45 It will be noted by referring to the showing of the blades in Fig. 1, that the partitions 40 on each blade are arranged with their ends in overlapping relationship to each other and to the guiding surfaces so as to prevent a direct or straight line passage of the steam in a line parallel to the shaft; consequently since the partitions on successive blades are inclined in opposite directions none of the steam can flow through the 50 turbine without being subjected to successive radial reversals of direction and as a result an additional propulsion effect is imparted to the turbine. By overlapping relationship is meant that the outer end of 55 any partition, (or lower guiding surface), is farther from the axis than the inner end of the next outer partition.

While, for the purpose of this application, I have only illustrated a single stage turbine 60 in the drawings, it will be understood that

the principles of construction disclosed are equally applicable to multi-stage turbines. It will also be understood that the partitions 40 may be dispensed with in the rotor and stator elements adjacent the entrance end 70 and that any suitable number of said partitions may be employed in the blades of any of the elements.

Various changes in the specific form shown and described may be made within 75 the scope of the claims without departing from the nature of my invention.

I claim:

1. In a turbine, a plurality of stator and 80 rotor elements each consisting of a plurality of blades arranged in spaced relationship, each of said blades having a pair of radially extending walls inclined to each other and to the longitudinal axis of said turbine, means extending from one of said walls to the adjacent blade and forming therewith an expansion chamber, and means extending from the other of said walls and forming therewith a plurality of inclined nozzles.

2. In a turbine, a plurality of stator and 85 rotor elements each consisting of a plurality of blades arranged in spaced relationship, each of said blades having a pair of radially extending walls inclined to each other and to the longitudinal axis of said turbine to 90 produce substantially longitudinal deflections in the direction of the flow of the fluid passing through said turbine, means extending from one of said walls to the adjacent forward blade and forming therewith an expansion chamber and means extending from the other of said walls to said adjacent blade and forming therewith a plurality of inclined nozzles, the expansion chambers 95 and nozzles formed by the blades of each successive stator and rotor element increasing 100 gradually in size from the entrance to the delivery end of said turbine.

3. In a turbine, a plurality of stator and 110 rotor elements each consisting of a plurality of blades arranged in spaced relationship, each of said blades having radially extending walls arranged at an angle to each other and to the longitudinal axis of said turbine to produce substantially longitudinal deflections in the direction of the flow of the fluid passing through said turbine, and inclined guiding surfaces extending from said walls to produce a series of deflections in the flow 115 of said fluid having a radial component, and partitions extending from said walls in overlapping relation to said guiding surfaces to prevent a straight line flow of said fluid through said turbine and to form with said inclined surfaces a plurality of inclined 120 nozzles.

4. In a turbine, a casing, a plurality of ring structures, said casing and ring structures being provided with T slots, a plurality of turbine blades each having an at- 125

tachment portion comprising a **T** shaped head adapted to be detachably engaged within said **T** slots, said **T** shaped heads being of slightly less thickness than the distance between the walls of the leg portions of said **T** slots to permit said **T** heads to be inserted into said slots at any point thereof, the side edges of said **T** heads extending at right angles to the front and rear faces thereof, and the distance between said side edges being substantially equal to the distance between the widest portions of said **T** slots whereby the said edges of said **T** heads when turned into locked position within said slots will frictionally engage said slots to hold said blades securely in operative position and diagonally opposite corners of said

side edges being rounded to permit said **T** heads to be turned to locked position.

5. In a turbine, a plurality of stator and 20 rotor elements each of said elements being provided with a plurality of expansion chambers and a plurality of inclined guiding surfaces adjacent to each expansion chamber to form a plurality of inclined nozzles 25 to direct the fluid passing through said turbine into said expansion chambers, said expansion chambers and nozzles being arranged in alternation from the entrance end to the delivery end of said turbine. 30

In testimony whereof I have signed this specification.

HERMANN T. WERBER.
